United States Patent Office

Des. 185,906
Patented Aug. 18, 1959

185,906

HANGING ORNAMENT OR SIMILAR ARTICLE

Jack Burnbaum, Newton, Mass.

Application November 20, 1958, Serial No. 53,456

Term of patent 14 years

(Cl. D29—1)

Fig. 1.

Fig. 2.

Fig. 1 is a front elevational view of a hanging ornament showing my new design; and

Fig. 2 is another elevational view looking from the right of Fig. 1.

I claim:

The ornamental design for a hanging ornament or similar article, substantially as shown.
